UNITED STATES PATENT OFFICE.

BERNARD TORRINGTON MONIER-WILLIAMS, OF ISLINGTON, LONDON, ENGLAND.

DEVICE FOR THE PREVENTION AND CORRECTION OF PROTRUDING EARS.

1,050,744.

Specification of Letters Patent. Patented Jan. 14, 1913.

Application filed May 4, 1912. Serial No. 695,153.

To all whom it may concern:

Be it known that I, BERNARD TORRINGTON MONIER-WILLIAMS, a subject of the King of Great Britain, residing at 88 High street, Islington, London, England, have invented 5 a new and useful Device for the Prevention and Correction of Protruding Ears, of which the following is a specification.

This invention relates to a device by means 10 of which persons with protruding ears may cause them to assume a position close to the sides of the head.

My invention in its most approved form 15 is illustrated in the accompanying drawing, which is shown on an exaggerated scale for the sake of clearness.

In the said drawing:—Figure 1 is an edge view of the device. Fig. 2 is a face view thereof. Fig. 3 is a face view with a portion of an outer layer removed. Fig. 4 is an 20 edge view with one of the outer layers partly detached, and Fig. 5 shows a human ear with the device which forms the subject of this application indicated in dotted lines in 25 position behind the same.

The device or appliance in the forms shown consists of a pair of adhesive disks a, a' placed back to back and secured together by thread or silk b , so that they are 30 a suitable distance apart. The disks are preferably made each of two layers, and two threads are employed for attaching the disks together. In the construction shown in Figs. 1 and 2 the threads are passed through 35 the center of the inner layers and the ends are separated diametrically of the disks and tied at the edges as indicated at c, c' . The two layers of each disk are then stuck together by suitable adhesive material. The 40 arrangement illustrated in Figs. 3 and 4 is the same except that the ends of the thread are not tied, the adhesive material which se-

cures the layers together being relied on to hold the thread.

The disks a, a' are coated with material 45 on the outer sides which can be made to adhere when placed behind the ear so as to stick to the latter and to the sides of the head, and retain the ear in the position determined by the length of the thread attachment between the disks. A suitable adhesive 50 which I have found to give good results in practice is spirit gum.

The disks may be made of various materials, for instance metal or celluloid but 55 preferably the outer layers are of silk while the inner layers are of stronger or coarser material such as fine canvas.

Instead of disks little plates of other form 60 may be used.

Claims:

1. An appliance for retaining an ear in a desired position, comprising a construction formed of two parts and inwardly yielding means connecting the inner sides of said 65 parts and holding them a certain distance from each other, the outside of each part being provided with an adhesive substance whereby one of said parts may be made to adhere to the ear and the other to the head. 70

2. An appliance for retaining ears in a desired position, consisting of a pair of disks, each disk of said pair, comprising two layers of material, and means for securing the disks a predetermined distance 75 apart, the layers of each disk being adapted to be secured together, the outside of the outer layer of each disk, being provided with an adhesive substance.

BERNARD TORRINGTON MONIER-WILLIAMS.
